UNITED STATES PATENT OFFICE.

MARK S. LEVERING, OF PHILADELPHIA, PENNSYLVANIA, ASSIGNOR TO THE STANDARD HOSE MENDER AND PIPE COUPLER COMPANY, OF CAMDEN, NEW JERSEY.

DESIGN FOR A MEMBER FOR HOSE-COUPINGS.

SPECIFICATION forming part of Design No. 32,963, dated July 17, 1900.

Application filed June 2, 1900. Serial No. 18,899. Term of patent 14 years.

To all whom it may concern:

Be it known that I, MARK S. LEVERING, a citizen of the United States, residing at the city of Philadelphia, in the county of Philadelphia and State of Pennsylvania, have invented and produced a new and original Design for a Member for a Hose-Coupling, of which the following is a specification, reference being had to the accompanying drawings, forming part thereof, in which—

Figure 1 is a side elevational view of a member for a hose-coupling of the design of my invention. Fig. 2 is a front end view, and Fig. 3 is a rear end view, of the same.

As illustrated in the drawings, the leading or material feature of my design consists of an outer barrel A, one end whereof is notched or indented, as at a, an inner tube B, and an

inner wall C, the latter integrally uniting the inner tube and outer barrel. The extension 20 of the inner tube beyond the wall C is formed into threads d, as clearly illustrated in Fig. 1 of the drawings.

Having thus described my invention, what I claim as new, and desire to secure by Letters 25 Patent, is—

The design for a member for a hose-coupling, substantially as herein shown and described.

In testimony whereof I have hereunto set 30 my signature in the presence of two subscribing witnesses.

MARK S. LEVERING.

Witnesses:

THOMAS M. SMITH,
J. WALTER DOUGLASS.
